US00D720539S

(12) **United States Design Patent**
Scott

(10) **Patent No.:** US D720,539 S
(45) **Date of Patent:** ** Jan. 6, 2015

(54) **BOX**

(76) Inventor: **William Mitchell Scott**, Villa Hills, KY (US)

(**) Term: **14 Years**

(21) Appl. No.: **29/431,504**

(22) Filed: **Sep. 7, 2012**

(51) **LOC (10) Cl.** 03-01

(52) **U.S. Cl.**

USPC **D3/307**

(58) **Field of Classification Search**

USPC D3/302, 304-305, 307-315; D34/1;
D19/75-76, 86, 90-91, 99-100;

(57) **CLAIM**

I claim the ornamental design for a box, as shown and described.

DESCRIPTION

FIG. 1 is an exploded perspective view of the box;

FIG. 2 is a perspective view thereof;

FIG. 3 is an exploded front view thereof, the back being a mirror image;

FIG. 4 is a front view thereof, the back being a mirror image;

FIG. 5 is an exploded side view thereof, the opposite side being a mirror image;

FIG. 6 is a side view thereof, the opposite side being a mirror image;

FIG. 7 is a top plan view thereof;

FIG. 8 is a bottom plan view thereof;

FIG. 9 is an exploded perspective view of a second embodiment of the box;

FIG. 10 is a perspective view thereof;

FIG. 11 is an exploded front view thereof, the back being a mirror image;

FIG. 12 is a front view thereof, the back being a mirror image;

FIG. 13 is an exploded side view thereof, the opposite side being a mirror image;

FIG. 14 is a side view thereof, the opposite side being a mirror image;

FIG. 15 is a top plan view thereof;

FIG. 16 is a bottom plan view thereof;

FIG. 17 is an exploded perspective view of a third embodiment of the box;

FIG. 18 is a perspective view thereof;

FIG. 19 is an exploded front view thereof, the back being a mirror image;

FIG. 20 is a front view thereof, the back being a mirror image;

FIG. 21 is an exploded side view thereof, the opposite side being a mirror image;

FIG. 22 is a side view thereof, the opposite side being a mirror image;

FIG. 23 is a top plan view thereof; and,

FIG. 24 is a bottom plan view thereof.

The broken lines shown in the drawings are for illustrative purposes only and form no part of the claimed design.

1 Claim, 21 Drawing Sheets
